TREATING HYDROCARBON FLUIDS

Homer J. Hall, Cranford, N. J., assignor to Standard Oil Development Company, a corporation of Delaware

Application December 15, 1943, Serial No. 514,334

2 Claims. (Cl. 196—52)

1

This invention relates to treating hydrocarbon fluids, and more particularly, relates to the production of aviation gasoline blending stocks.

Catalytic cracking of petroleum fractions produces gasoline having a relatively high proportion of aromatic constituents, especially when using relatively high temperatures. At the same time, olefins, paraffins and naphthenes are formed. The higher boiling aromatic constituents containing side chains are too high boiling for aviation gasoline.

According to my invention, a catalytically cracked naphtha fraction having a higher initial boiling point than the final boiling point of aviation gasoline is cracked under severe conditions to reduce the boiling points of the aromatic constituents. If no steam is added as diluent during the cracking under these severe conditions, a relatively small amount of paraffins is destroyed but an appreciable amount of the higher boiling aromatics are cracked down into aromatics within the aviation gasoline boiling range. If steam is added in relatively large amounts as a diluent, more paraffins are destroyed and the aromatics are broken down in a lesser degree. In the preferred form of my invention, no steam is added to the cracking zone but in some cases I may add steam as a diluent to reduce tar and coke formation.

The final boiling point of aviation gasoline may vary between rather wide limits. These limits are dictated partly by the maximum aromatic content desirable, the high octane value of these aromatics, and the manufacture of maximum yields of aviation fuel from a given amount of feed stock. These factors are balanced against the increasing difficulty of maintaining good fuel distribution in a carburetted multicylinder engine as the fuel volatility decreases. Under various circumstances aviation fuels having end points varying from 250° to 350° F. have been used, with the range from 295° to 335° F. being more common.

For purposes of illustration, the present invention will be described in terms of a fuel having a final boiling point of 320° F., it being understood that the choice of this particular temperature is not to be construed as a major part of the invention or a limitation thereon.

An important purpose of my invention is to permit the use of existing thermal equipment for upgrading catalytic heavy naphtha boiling above the aviation end point, to give an additional yield of high quality aviation fuel with-

2

out requiring additional catalytic cracking plant capacity.

Another purpose of my invention is to crack an aromatic heavy naphtha under severe conditions so as to break down non-aromatic materials completely into more desirable light gases, while leaving the aromatics with only a slight decrease in boiling range, sufficient to bring them into the aviation fuel boiling range.

More specifically, my invention comprises selecting a catalytically cracked naphtha having a boiling range of about 320° to 450° F. and thermally cracking it at a temperature of about 1200° F. to 1450° F. for a few seconds or less and then separating a fraction of about 220° F. to 320° F. boiling range. The resulting fraction contains a high concentration of aromatics which are desirable constituents in aviation gasoline or aviation gasoline blending stocks.

In the drawing, I have shown one form of apparatus which may be used in carrying out my process.

Referring now to the drawing, the reference character 10 designates a line for conducting hydrocarbon oil or vapors to be cracked. The oil may comprise any relatively heavy hydrocarbon, such as gas oil, and the hydrocarbon may be in vapor or liquid form. When used as a liquid, the fraction is partly preheated and mixed with a sufficient amount of catalyst or catalyst plus inert solids to raise the hydrocarbon oil to cracking temperature and to supply the heat of cracking.

Powdered catalyst is introduced into line 10 from line 12. Line 12 is supplied with catalyst from a hopper 14. Instead of using powdered catalyst, stationary beds of pill catalyst or moving beds of granular catalyst may be used. Where powdered catalyst is used, the particles have a size between about 200 to 400 standard mesh or finer. Any suitable cracking catalyst may be used, such as acid-treated bentonites, synthetic silica alumina gels, synthetic silica magnesia gels, etc. I prefer to use the synthetic silica alumina gels as they produce more aromatics at the temperatures used.

The mixture of hydrocarbon oil and powdered catalyst at a temperature of about 900 to 1000° F., preferably 975° F., is passed through line 16 into the bottom portion of a reaction zone 18. Catalyst and oil feed rates and contact times are adjusted so as to give a ratio of about one ton of oil per hour per ton of catalyst in the reactor, with a catalyst/oil weight ratio of the order of 20 to 1. The products of conversion in vapor

form, together with entrained catalyst, pass overhead from the reaction zone 18 through line 22 and are passed to a separating means 24 for separating entrained catalyst from dry reaction vapors. More than one separating means may be used. The separated catalyst particles drop into the bottom of the separating means 24 and are withdrawn through line 26. The catalyst particles are regenerated in any suitable manner and returned to the hopper 14 for reuse in the process.

The reaction vapors leave the separating means 24 through line 28 and are cooled by cooler 30 and then introduced into a fractionating tower 32. Uncondensed vapors and gases pass overhead through line 34 and condenser 36 and the cooled and condensed vapors are passed to a separator 38 for separating C₄ hydrocarbon gases and lighter from liquid. The C₄ and lighter gases pass overhead through line 42 and may be treated in suitable equipment to separate and recover desirable constituents for alkylation, isomerization, dehydrogenation, etc.

The condensed liquid is withdrawn from the bottom of the separator 38 through line 44 and at least a portion thereof is returned to line 46 by pump 48 to the upper portion of the fractionating tower 32 as reflux. At least a portion of the liquid is withdrawn from the system through line 52. This light fraction has a boiling range of about 60° F. to 200° F., referred to as a C₅-200° F. cut, and may be added to aviation fuel. Also, this C₅-200° F. cut may be hydrogenated (converting C₅ olefins into valuable isopentane) or acid-treated or catalytically after-treated.

A heavier cut, 200-320° F. is withdrawn from the tower 32 as a side stream through line 53. This cut may be used in aviation gasoline as is or it may be acid-treated, or in some cases may be catalytically after treated.

A relatively heavy naphtha is withdrawn from the fractionating tower 32 through line 54 and is further treated as will be presently described. A heavier fraction may be withdrawn through line 56 and used as heating oil, cycle stock, or in any other way desired. Condensate oil containing cycle stock and some entrained catalyst which was carried over with the vapors is withdrawn through line 58. If desired, the condensate oil may be recycled to the reaction zone 18 or it may be filtered or settled to recover the catalyst therefrom.

Returning now to the heavy naphtha fraction withdrawn through line 54, this fraction has a boiling range of about 320° F. to 450° F. and contains aromatic constituents together with non-aromatic constituents. The initial boiling point of this fraction is dictated by the end point of the lower boiling aviation fuel, which may vary from 250 to 350° F., as discussed above, or more generally, from 295 to 335° F. The end point of the heavy naphtha fraction may vary from 410° to 500° F. or as high as 600° F., with the higher boiling range giving increased total yields accompanied by an increased formation of tar and coke in the subsequent cracking step. A typical composition of this fraction is as follows:

Per cent by volume	
Aromatics	85 to 95
Paraffins	0 to 5
Naphthenes	0 to 5
Olefins	0 to 5

The heavy naphtha fraction is passed through line 58 by pump 62 and may be mixed with a

4
diluent such as steam introduced through line 64. In the preferred form of my invention where it is desired to break down side chains or higher boiling aromatics, I prefer to omit steam as a diluent. In some cases it may be desirable to use 80 mol per cent of steam to reduce tar formation. The heavy fraction is passed through heating coil 66 in a furnace or heater 68 wherein it is heated to about 1050° F. to 1450° F. for about 10 100 seconds to 0.1 second, the shorter times being used for the higher temperatures. The products of conversion are passed through transfer line 72 into a quenching zone 74, together with quench oil introduced into transfer line 72 through quench line 76. In this transfer line and quenching zone the temperature of the reaction products is quickly reduced to avoid undesirable reactions. Uncondensed vaporous products pass overhead through line 78, and any heavy tar which separates out is withdrawn through line 80.

The overhead from the quenching zone and separator 74 passes through line 78 to fractionating tower 82. From this tower the light gases and uncondensed vapors pass overhead through line 84. These gases may be passed through an absorption tower or other suitable equipment, to recover olefins and other desirable hydrocarbons. An additional side stream representing butanes, pentanes and other light liquid products may be withdrawn through line 86. A desired aromatic product fraction boiling between about 220° F. and 320° F. is withdrawn as a side stream through line 88. A heavier tar-free cycle stock is withdrawn from the bottom of tower 82 through line 90. A portion of this cycle stock goes as quench oil, through line 76. Another portion may, if desired, be recycled to the cracking step through line 94 opening into line 54. The remainder of the cycle stock is withdrawn at 96.

40 The fraction withdrawn through line 88 is within the aviation gasoline boiling range and contains a large percentage of aromatic constituents. The fraction has the following composition:

	Per cent by volume
Aromatics	95 to 100
Naphthenes	0 to 2
Olefins	0 to 5

50 During the severe cracking in coil 66 the higher boiling aromatics are broken down to form aromatics which boil in the aviation gasoline boiling range. It will be seen that the fraction going to the thermal cracking zone 66 has a boiling range 55 above that of aviation gasoline. After the severe cracking a fraction boiling in the aviation gasoline is recovered.

During the cracking reaction, paraffinic compounds or long paraffinic side chains on aromatic compounds are broken down into smaller molecules. The aromatic nucleus is relatively much more stable under the conditions used, and aromatic fragments containing one or two methyl groups are a principal product. Practically no non-aromatic material remains in this boiling range, since the non-aromatic fragments are largely gaseous. As a result, the toluene-xylene fraction from 220-320° F. contains practically pure aromatics. Higher boiling cuts from the re-cracking stage will be equally aromatic when the aviation gasoline withdrawn from line 53 has a higher end point, since the aromatics present in any boiling range will crack down somewhat, while non-aromatics go all the way to light fragments. In various cases it may or may not be

desirable to include a benzene cut from 165-220° F. in the final product, depending upon the amount of non-aromatic material remaining in this portion of the product. The final yield of aromatic blending stock, depending on the severity of the re-cracking stage and the aromatic content of the feed stock, is about 10 to 30% by volume of the heavy naphtha fraction passing through line 54.

The following examples include data obtained by severe thermal cracking of a 335° to 410° F. heavy naphtha fraction obtained by catalytic cracking of gas oil having a boiling range of about 515° F. to 700° F., an API gravity of 32.4°, the catalytic cracking being carried out at a temperature of 975° F. with a catalyst comprising synthetic silica alumina gel. The ratio of catalyst to oil by volume in the catalytic cracking step was about 5.4 to one. Total motor gasoline yield in this one pass operation was about 42.3 volume % on feed stock, which is broken down into 22.9 volume % aviation naphtha stock, 12.1 volume % pentane and lighter, and 7.3 volume % of 335-410° heavy naphtha.

In one example, a heavy naphtha fraction comprising a 335-410° F. cut was treated in a heated coil at 1295° F., for a contact time of 3.3 seconds, in the absence of steam. The products recovered included 12.3 weight % of dry gas, 3.6 volume % of a light fraction from butane through 220° F., 50.9 volume % of cycle stock in the range of the feed, and 29.3 volume % of aromatic 220-335° product. The aromatic blending stock produced analyzed 97-100% aromatics and had a specific gravity of 0.871.

As a further example, I would state that superior results are obtained by carrying out the thermal re-cracking step at a temperature of about 1100° F. for a heating time not more than about 4 seconds. Also, if the re-cracking step be carried out at a somewhat higher temperature, to wit, at 1200° F., a shorter treating time of about 1 second is sufficient for satisfactory results.

A similar run on the same feed stock at 1250° F. coil temperature, for 3.5 seconds contact time in the presence of 78 mol % steam, gave 16.8 weight % dry gas, 6.0 volume % butanes through 220°, 59.6 volume % recovered as cycle stock having the initial boiling point of the feed, and 17.9% of aromatic aviation blending stock. The product in this case analyzed 96% aromatics.

While I have shown one form of apparatus in the drawing and have included examples of thermally cracking catalytically cracked heavy naphtha, it is to be understood that these are by way of example only and by illustration only, and various changes and modifications may be made without departing from the spirit of my invention.

I claim:

1. A method of producing aviation gasoline

blending stock which comprises catalytically cracking a relatively high boiling hydrocarbon fraction at a temperature of about 900° F. to about 1000° F. to produce lower boiling constituents containing aromatic constituents and paraffins, separating from the cracked products an aviation gasoline fraction and a heavy naphtha fraction higher boiling than the end point of the aviation gasoline fraction and containing aromatic constituents too high boiling for inclusion in aviation gasoline, said heavy fraction boiling between about 320° F. and 450° F., thermally cracking the said heavy fraction at a temperature of at least 1200° F. for a period of time not in excess of a few seconds to crack high boiling aromatic constituents to lower boiling aromatic constituents and separating from the products of the last cracking step a fraction within the aviation gasoline boiling range and containing substantially only aromatic constituents.

2. In a method of producing aviation gasoline blending stock wherein a hydrocarbon fraction is catalytically cracked at about 925° F. to about 1000° F. in the presence of synthetic silica alumina gel catalyst to produce lower boiling constituents in the gasoline boiling range and containing aromatics, the steps which include separating from the cracked products a fraction having a boiling range of about 320° F. to about 450° F., heating the said separated fraction under non-catalytic conditions for about 1 second to a higher temperature than used in the catalytic cracking step and of the order of 1200° F. to reduce the boiling point of higher boiling aromatics and separating from the last mentioned heating step a fraction containing aromatics and boiling below about 320° F.
